UNITED STATES PATENT OFFICE

S. M. BULLARD, OF HOLLISTON, MASSACHUSETTS.

DOOR-HINGE.

Specification of Letters Patent No. 17,419, dated June 2, 1857.

To all whom it may concern:

Be it known that I, S. M. BULLARD, of Holliston, in the county of Middlesex and State of Massachusetts, have invented a new 5 and useful hinge for doors, gates, blinds, or shutters for the purpose of closing the same by their own weight as the motive power, which I have named a "Self-Closing Door-Hinge;" and I do hereby declare that 10 the following is a full and exact description thereof.

My hinge consists of four pieces or parts made of iron or other metal, and for a better understanding of its form and operation, 15 reference is here made to the accompanying drawings.

What I claim as my invention, is the detached antifriction roller, grooved or hollowed on its edge moving between two circular inclined planes, which are formed 20 upon the edges of cup-shaped pieces, connected with the flanges of the hinge, the upper inclined plane to the flange attached to the door, and the lower inclined plane to the 25 flange attached to the door frame.

Figure 1 is a sectional view of the hinge when closed. Fig. 2 is a view of the hinge one quarter open, or in the position it would be when the door was at right angles to its 30 frame. Fig. 3 is a sectional view of the hinge when open, or with the door back against the wall. Fig. 4 is a view of the spindle, shaft or pin upon which the other parts are operated. Figs. 5 and 6 the roller.

A, Figs. 1, 2, and 3, represents the cup-shaped part upon which is formed the lower inclined plane, and is attached to, or forms 35 a part of the flange which is fastened to the door frame; p , is the lower part of the same through which the spindle C, passes to give 40 it steadiness.

B, Figs. 1, 2, and 3, represents the cup-shaped part upon which is formed the upper inclined plane, and is attached to, or forms 45 a part of the flange which is fastened to the door; o is the lower part of the same through which the spindle C, passes to give it steadiness.

D, Figs. 2 and 5, represents, a front view 50 of the roller.

D, Fig. 6, represents sectional view of the roller, q , q , its groove or hollow which guides and retains it upon the inclined planes.

D, Figs. 1 and 3, represents a perspective 55 view of the roller.

E, Figs. 1, 2, and 3, represents the body part of the hinge, through which the spindle C, passes, and has a solid connection with the cup-shape parts A and B, and the flanges F. 60

n , v , n , Figs. 1 and 3, represent a sectional view of the cup-shaped parts A and B. n , v , n , Fig. 2, represents a front view of the same.

h , i , j , Figs. 1 and 2, represent the lower 65 inclined plane, and k , l , m , Fig. 2, represents the upper inclined plane.

D, Fig. 1, shows the roller at rest upon the point h , at the bottom of the lower inclined plane h , i , j , with the point k at the top 70 of the upper inclined plane k , l , m , resting upon the top of the roller D, consequently the whole weight of the door hangs or bears upon the roller, and as the door is opened the roller commences ascending the lower 75 inclined plane h , i , j , and the upper inclined plane k , l , m , passes up above, or over the roller D, as is shown in Fig. 2, where the hinge is one quarter open, and o , the lower part of B, has risen one half of the distance from p , to s , and the roller D, is seen in the middle of the inclined planes, between the points i and l . 80

D, Fig. 3, shows the roller at rest at the top of the lower inclined plane h , i , j , or 85 upon the level j , n , with the point m , or the level m , n , resting upon the top of the roller, and c , the lower part of B, raised the whole distance from p to s ; in this position the door will remain open, or stand at rest, but 90 if left free to itself at any intermediate point, its own weight will immediately cause it to close.

r , Figs. 2 and 3, represent the screw holes through the flanges F, and w , Fig. 3, represents the reaming or countersinks, for the 95 heads of the screws.

C, Fig. 4, represents the spindle, a , its head, the part immediately below the head, and from c to d , is made to fit tight in the 100 body of the hinge E, and the lower part of it o ; at b is made to fill the hole in the body of the hinge from g to f , (Fig. 1), but from b to c , and from d to e , it is made tapering, so as to avoid any friction that 105 would be occasioned by the center of this and the other hinges of the door not coming in an exact line with each other.

But one of these hinges is needed upon a door, the other or others should be the loose or slip hinges, allowing the door to rise as it opens, and descend as it closes.

- 5 This hinge can be made without the lower part, consisting only of the parts represented above the dotted line *t, u*, which passes through Figs. 1 and 4, and when thus made, but three pieces or parts are needed,
10 the spindle, shaft or pin can form a solid part of the body of the hinge *E*, this will lessen its cost, but it will not be as firm and steady as the one represented by my drawings. It can also be made with an upper
15 part corresponding with the lower part, which would add to its strength and firmness, and bring the inclined planes or cup-shaped pieces in or near the middle of the hinge.
20 I do not confine myself to any inclination, or length of the inclined planes, the steeper, or quicker the ascent of the inclined planes, the sooner, and with greater force will the door close; they may be made of any length,

so that the roller will pass on to a level and 25 allow the doors to rest, or stand open at any angle or position desired.

I do not confine myself to any size of the circle, or circumference of the inclined planes, their size or distance from the center 30 of the spindle may be varied at pleasure.

I do not confine myself to any size of the detached antifriction roller, its size is immaterial, the effect is the same.

I do not confine myself to any particular 35 outward form of the several parts, they may be made plain or ornamental at pleasure.

I do not claim the inclined planes as my invention, for they have been long known and used, but
40

What I do claim, is,

The detached antifriction roller, inserted between the inclined planes, in the manner and for the purpose above described.

S. M. BULLARD.
